[57] ABSTRACT

A device for examining pupillary reflex so constructed that a spotlight is applied directly or indirectly to an eye of a patient to cause pupillary reflex, an infrared lamp is provided to apply infrared rays to the eye for convenience of camera work, and an infrared camera and television set or screen are provided to catch and reproduce a motion of the pupil into an image. From the image of pupillary motion reproduced on the screen, an ophthalmologist can readily and exactly know the condition of retina, or optic nervous system, without any help of oral answer or sign of the patient.

OPHTHALMIC DIAGNOSTIC INSTRUMENT

CROSS REFERENCE TO PRIOR APPLICATION

This is a Continuation-in-Part of our copending application Ser. No. 834,041, filed June 17, 1969, now abandoned. Priority of corresponding Japanese applications Nos. 43 52595, filed June 22, 1968 and 44 51173, filed June 3, 1969 is claimed under the convention.

BACKGROUND OF THE INVENTION

1. Field of the Invention

The present invention relates to a device for examining pupillary reflexes, more particularly, to a diagnostic device of diseases in the optic nervous system or retina, through pupillary reflexes to light.

2. Summary of the Invention

If the eye is normal, the retina respond to illumination by its pupillary reflexes through the optic or brain nervous system, and any damage or disorder in the optic nervous system is known to cause various types of so-called star-blindness.

The objects of the invention are to provide:

a device for examining pupillary reflexes permitting as to check up on diseases to or damages in an optic nervous system or retina and measure a range of the field of vision, through the reflex motion of the pupil responsive to a given light;

to provide a device for examining pupillary reflexes so constructed that as a patient is kept within a dark environment, the motion of his pupil to a given light is detected, under radiation of infrared rays by an infrared ray camera and reproduced on the screen of a television set, whereby a contraction of the pupil responsive to the light is exactly observed in detail without the necessity of a consultation with a patient. Thus any person having difficulties of communication including the asphasic, the older person or a child and any patient with general paralysis may be easily examined; to provide a device for examining pupillary reflexes so including a light source for directing a spotlight to the eyeball of a patient with a number of lamps mounted on a rotary arm member, said means to switch them on and off in sequence, and

the device of the invention in a design which is very simply manufactured at a low cost.

BRIEF DESCRIPTION OF THE DRAWINGS

FIG. 1 is a diagram of an embodiment of the device of the present invention, showing a spotlight applied to a hemispherical screen;

FIG. 2 is a plan view of a means to control the direction of a spotlight employed in the device for examining pupillary reflex shown in FIG. 1;

FIG. 3 is a cross-sectional view of a light-projecting section of the device shown in FIG. 1;

FIG. 4 is a side view of a means to adjust the position of a chin support employed in the device shown in FIG. 1;

FIG. 5 is a perspective view of another form of a device for examining pupillary reflex;

FIG. 6 is a side view of the substantial part of the device shown in FIG. 5;

FIG. 7 is a cross-sectional view of a rotary arm member employed in the device shown in FIG. 5;

FIG. 8 is a side view of a means for adjusting the height of a pillow employed in the device shown in FIG. 5;

FIG. 9 is a view partly in cross section of a means for adjusting the lateral position of a casing employed in the device shown in FIG. 5;

FIG. 10 is a diagram of a circuit for controlling a rotation angle of the rotary arm;

FIG. 11 is a view of a part of a means for driving the rotary arm;

FIG. 12 is a plan view of a switch panel employed in the device shown in FIG. 5;

FIG. 13 is a side view of a part of the switch panel shown in FIG. 12; and

FIG. 14 is a diagram of a circuit for driving lamps on the rotary arm shown on FIG. 7, showing also the circuit connections between lamps and switches on the switch panel shown in FIG. 12.

DESCRIPTION OF THE PREFERRED EMBODIMENTS

Device for eye examination in the erect position of patients. In FIGS. 1 through 4, there is illustrated one embodiment of the present invention, preferably for eye examination of the patient in a standing or sitting position. A screen of a hemispherical shape or a substantially hemispherical shell extending to cover the entire range of the visual angle of the eyeball, is mounted relative to the unit 2 for applying a spotlight, and controlling its direction to any desirable spot visible within the extension of the internal wall of said screen 1. The amount of light and the time of lighting can be controlled.

Means to control the direction of illumination

35 a vertical arm of the unit 2 is pivotally connected to the body thereof with the pivotal connecting point positioned in alignment with an imaginary line between the center and the apex of the hemispherical screen 1. The unit 2 is adapted to rotate by 180°, to permit the pivotal connecting point as a fulcrum over the head of a patient by the operation of a handle 2f. A line 2c is stretched across a wheel 2d and a wheel 2b through pulleys. The wheel 2b is connected to a frame of a light projecting section 2a of the unit 2 and adapted to move with it. The wheel 2d is connected to a control wheel 2e and adapted to be rotated by it. Then the wheel 2b and the light projecting section 2a are rotated by the movement of the line 2c. The unit 2 for applying the spotlight comprises a lamp 2g, a lens 2h for focusing the light from the lamp 2g, a stop 2i for controlling the amount of the light and a reflective element 2j adapted to reflect and direct the light transmitted through the stop 2i. A timer is connected to control the duration of illumination of the spotlight on the screen 1. Thus, a spotlight is applied to any desirable location of the screen by operations of the control wheel 2e and the handle 2f. A chain support 3 for the patient 4 is adjustable to set the patient's eye 4a to the level in alignment with a camera lens.

Means to control the position of a chin support

As shown in FIG. 4, the chin support 3 is disposed at the top end of a shaft 3f which has a handling wheel 3e at its other end. The shaft 3f has a threaded portion and is inserted, through a threaded bore of a sliding plate 3a engaged with the threaded portion of the shaft 3f, in a guiding groove formed on the frame of the unit 2. Thus, by operating the handling wheel 3e, the chin sup-

port 3 can be moved upwardly or downwardly to adjust the patient's eye to a required position. The chin support is free from the rotation of the shaft 3f. Through the sliding plate 3a a shaft 3b is inserted, which has a threaded portion on either end portion of the shaft 3b. Two blocks 3c are fixed to the frame of the unit 2 and each has a threaded bore engageable with the threaded portion of the shaft 3b. Handling wheels 3d are provided on the ends of the shaft 3b, respectively. The shaft 3b is freely rotatable relative to the sliding plate 3a but is fixed with reference to the axial direction of the shaft 3b by a stop rings 3g. Accordingly, by operation of the handling wheel 3d, the sliding plate 3a is moved to adjust the lateral position of the chin support 3.

Diagnostic detection and presentation

An infrared ray television camera 5 is mounted on the hemispherical screen 1 at the apex thereof, and, an infrared lamp 6 is spaced therefrom to emit, from which infrared rays directed to the pupil of the patient's eyeball, so that the television camera can detect a transient motion of the pupil responsive to the light given thereto. An image receiving section 7 or a reproducing screen such as a Braun tube is aligned with the television camera to reproduced the pupillary reflexes into an image.

The operation

The chin rest 3 is adjusted to set the patient's eye into alignment with the center of the screen 1 and the television camera 5, and the spotlight is applied to the eye through the screen 1. The infrared rays are applied to the eye, so that the pupillary reflex to a given illumination by the spotlight is detected by the infrared camera and reproduced into an image on the screen of the image receiving or reproducing section 7. A pupil is sensitive to ambient visible light and therefore the inner part of the screen 1 covering the entire visual field of patient must be kept dark. A spotlight illumination is applied from the spotlight applying unit 2. To one or an other spot along and on the internal surface of the screen 1. The lamp 2g is not lit before the shifting operation of the spotlight applying unit 2 has been finished. After completion of the shifting operation, the lamp 2g is energized for a period of time determined by the timer, for examples, for 4 seconds.

The pupil does not respond to the infrared rays, but responds only to the visible light of spotlights.

The spotlight applying unit 2 is operated to shift a spot of light from one position to another within the internal surface of the screen 1, with variations of intensity of light, and an image of a transient reflex motion of the pupil is received on the screen of the receiving section 7. From this, any one can make a diagnosis whether there is something abnormal in the retina at the location corresponding to the position of the spot light.

If a smaller or larger quantity of spotlight is movably applied at a fixed interval of time or an irregular interval of time to any point throughout the internal surface of the screen 1, the motion of the pupil responsive to such spotlight in the darkness will be instantaneously reproduced on the television screen and will clearly show the condition of the retina or the optic nervous system and a range of the visual field of the patient. Device for eye examination with patient in prone position

In FIGS. 5 through 14 another embodiment of the present invention is shown. A bed 11 is provided for a patient, with an operation table 12, on which is mounted a casing 13 having one open end 13a at its front side and by which the upper half of the patient body is covered. The open end 13a has a shielding curtain 13b for preventing the outer light from entering the casing 13.

The casing 13 has a television camera 15 mounted on its top and lined up to detect the motion of the pupil by the employment of infrared ray emitted from units 16, which are mounted on a slanted wall of the casing 13. A rotary arm control of illumination

An arch-shaped rotary arm 17 secured to the upper 15 internal wall of the casting 13, has an arm portion, a central hole 17a through which a lens barrel 15a of the television camera 15 protrudes into the casing 13, and an upper disc portion 17b provided with annular racks 17c. The rotary arm portion 17 has an internal surface 20 provided with a number of lamps grouped in sets of three and arranged radially in three rows, lamps in one row having diameters different from those of the other two rows, the left lamps being the largest, the right lamps being the smallest in diameter and those of the 25 mid row being of an intermediate size as shown in FIG. 7.

A driving mechanism 18 consisting of a motor 18a and a gearing mechanism 18b, including a spur gear 18c, meshing with racks 17c is mounted on the disc 30 portion 17b of the rotary arm 17 in meshed relation through gears, so that one rotation of the motor 18a causes a full turn of the rotary arm 17. The spur gear 18c engages with a gear 18d as shown in FIG. 11. To the shaft of the gear 18d is connected a potentiometer 35 18e for detecting the position of the rotary arm 17. The switch panel

Two infrared lamps are provided in such arrangement that one of the infrared lamps still applies its rays to the pupil, when rays of another lamp are instantaneously intercepted by the rotary arm during rotation thereof. By rotating the rotary arm 17, a substantially hemispherical canopy provided with lamps on its internal surface is formed.

A switch panel 19 or an operation panel including a dial plate 19a is provided rotatably operative to drive the rotary arm 17 through the driving mechanism 18, by the same angular extent that said dial plate 19a is turned, and push buttons which are pressed to turn on a desired lamp 17d of the rotary arm 17, through a shift register 19n shown in FIG. 14. The push buttons comprise a illumination switch 19e, a switch 19f for shifting the position of a light inwardly, a switch 19g for shifting the position of the light outwardly, a resetting switch 19h, a switch 19i for selecting the size of the light, a switch 19j for switching the illumination of the lamps from one arm portion of its rotary arm 17 to the other arm portion, an indicator 19k for indicating the size of the lamp and a switch 19l for selecting the intensity of the light. The energized lamps are indicated on the switch panel 19. The dial plate 19a and an indicator 19m provided on the switch panel 19 for indicating the position of an energized lamp on the rotary arm 17 are connected through pulleys and belts as shown in FIG. 12. To the shaft of the dial plate 19a is connected a potentiometer 19d for detecting the position or rotation angle of the indicator 19m. When the dial plate 19a is turned, the potentiometer 19d is rotated and a voltage

corresponding to the rotation angle of the dial plate 19a is produced. Due to this voltage, the balance between the resistances of the potentiometers 19d and 18e are broken, producing a difference in voltage, which is amplified by an amplifier 19c and applied, as shown in FIG. 10, to the motor 18a to rotate it by a rotation angle corresponding to said difference in voltage. The rotation of the motor is stopped when the resistances of the potentiometers 19d and 18e are balanced. Accordingly, the rotary arm 17 is rotated in proportion to the rotation angle of the dial plate 19a and the rotation angle of the indicator 19m. The gear ratio of the gearing mechanism 18b, the spur gear 18c and the rack 17c are scaled to make the rotation angle of the potentiometer 18e proportional to the rotation angle of the rotary arm 17.

The illumination circuitry

As can be seen from the circuit diagram of FIG. 14, a plurality of lamps $l_{11}, l_{12} \dots l_{112}$ having the largest diameter, lamps $l_{21}, l_{22} \dots l_{212}$ having the intermediate diameter and lamps $l_{31}, l_{32} \dots l_{312}$ having the smallest diameter are arranged in three rows on one arm portion of the rotary arm 17. Similarly, a plurality of lamps $l_{11'}, l_{12'} \dots l_{112'}$ of the largest diameter, lamps $l_{21'}, l_{22'} \dots l_{212'}$ of the intermediate diameter and lamps $l_{31'}, l_{32'} \dots l_{312'}$ of the smallest diameter are arranged on the other arm of the rotary arm 17. The switch 19g for shifting the position of the light outwardly is connected to a NAND gate 19o and one pulse is produced by one operation of the switch 19g through said NAND gate 19o. The shift register 19n is connected to said NAND gate 19o and adapted to outwardly shift the position of a terminal in to a high level by operating the switch 19g. In the similar way, the switch 19f for shifting the position of the light inwardly is connected to a NAND gate 19p and one pulse is produced by every operation of said switch 19f through said NAND gate 19p. The shift register 19n is further adapted to inwardly shift the position of a terminal into a high level by the operation of the switch 19f. A timer 19b is adapted to close its contacts, for example, for 4 seconds, by closing the illuminating switch 19e. The resetting switch 19h is adapted to reset the shifting of illumination to the lamp $l_{11}, l_{21}, l_{31}, l_{11'}, l_{21'}, l_{31'}$ disposed at the most inward position of the respective arm portion of the rotary arm 17. The switch 19i has three fixed contacts respectively for lamps of the largest diameter, lamps for intermediate diameter and lamps for the smallest diameter.

Lamps $l_{41} \dots l_{412}$ and $l_{41'} \dots l_{412'}$ are indicating lamps symmetrically arranged on the indicator 19m. Transistors Tr_1 and Tr_1' are connected at their respective bases to a first terminal of the shift register 19n and adapted to be turned on when the terminal is in a high level. Transistors Tr_2 and Tr_2' , transistors Tr_3 and Tr_3' are connected through the respective bases to a second and a third terminal of the shift register 19n, respectively. Similarly, the remaining transistors are connected to the corresponding terminals of the shift registers, respectively. The transistors are turned on when the respective corresponding terminals are in a high level.

Thus as shown on FIG. 14 when the switch 19l for selecting the intensity of the light of the lamp is closed; the movable contact of the switch 19j is closed to its contact connected to the lamps on the left arm portion of the rotary shaft 17. The movable contact of the

switch 19i is closed to its lowest contact in FIG. 14 which is a contact for lamps of the largest diameter in the present embodiment; and the first terminal of the shift register 19n is in a high level, the transistor Tr_1 connected to said first terminal of the indicator 19m is turned on and the lamp l_{41} connected to said transistor Tr_1 is energized. Thus, on the indicator 19m, the lamp l_{41} is lit to indicate the position of the lamp l_{11} to be lit on the arm 17. Under this condition, when the switch 19e is closed, the timer 19b is operated for the determined period of time. Then, the transistor Tr_1 connected to the first terminal of the shift register 19n in a high level is turned on and a current is applied through the switches 19l, 19j and 19i to light the lamp l_{11} for the determined period of time. Then, the switch 19g is operated, the position of the terminal in a high level is shifted outwardly to the next terminal through the NAND gate 19o and the transistor Tr_2 is turned on to light the lamp l_{42} on the indicator 19m for indication of the position of the lamp to be lit. In the state, when the switch 19e is closed, the lamp l_{12} on the rotary arm 17 is lit in the same manner as mentioned above. By operating the switch 19g, the lamp to be lit is thus shifted outwardly, while by operating the switch 19f, the light to be lit is shifted inwardly due to the action of the NAND gate 19p.

When the switch 19l is opened, a current is reduced by a resistor connected in parallel with said switch 19l and the intensity of the light of the lamp on the rotary arm 17 is lowered.

By closing the movable contact of said switch 19j to the other contact, the lamps on the other arm portion of the rotary arm 17 are energized. By switching the movable contact of the switch 19i to another contact, lamps of intermediate diameter or lamps of the smallest diameter are to be lit.

Thus, the position of the lamp to be lit is controlled by the switches on the switch panel 19 and the lamp energized is identifiable on the switch panel 19. Stated illustratively, from the indicator 19m can be seen a longitudinal position of the lamp energized or to be energized on the rotary arm 17 and from the indicator 19k can be seen the size of the lamp energized or to be energized, or a lateral position thereof on the rotary shaft 17. A television set 20 transmits a motion of the pupillary reflex detected by the infrared ray camera 15 into an image. Knobs 21 and 22 are provided adjacent each other on the upper surface of the operation table 12, knob 21 operable for moving the pillow 12a vertically to adjust the level of the patient's eye; and knob 22 operable for moving the casing 13 in a transverse direction according to the position of the patient's eye.

Means to position patient for diagnostic examination

As shown in FIG. 8, when the knob 21 is turned, a gear 21a fixed to it is rotated, to rotate in turn a gear 21b meshed with the gear 21a. This rotation of the gear 21b is conveyed to bevel gears 21d and 12d through a universal joint 21c. A pillow shaft 12c has a threaded portion and a nut 12b, fixed to the operation table 12, has a threaded bore engageable with it. By turning the knob 21 (FIGS. 5 and 9) the pillow shaft 12c is rotated to move the pillow 12a upwardly or downwardly for adjusting the patient's eye to the required vertical position. For adjusting each of the patient's eyes to the required lateral position in alignment with the axis of the television camera barrel 15a, the knob 22 (FIGS. 5 and 9) is turned to move the casing 13 laterally. As shown

in FIG. 9, when the knob 22 is turned, a shaft 22a connected thereto is rotated. It has a threaded portion and a sliding means 22b with a threaded bore engageable with the threaded portion of the shaft 22a. Accordingly, the rotation of the shaft 22a moves the 5 sliding means 22b laterally. Thus, the casing 13 is moved laterally according to the movement of the sliding means 22b. A guiding means 12e is provided for the lateral movements of the casing 13.

The operation

The patient 14 lays on his back on the bed 11; his head is moved into the casing 13 on the operation table 12 through the opening 13a and rests stationary on the pillow 12a. The knob 22 is operated to move the casing 13 transversely to the position where the television camera 15 can scan exactly the eye to be examined. Thereafter knob 21 is operated to adjust the level of the pillow 12a, so as to locate the patient's eyeball at the center of said rotary arm 17.

Subsequently, buttons of switch panel 19 are pressed to an operative position to energize three lamps 17d positioned at the end portion of the rotary arm 17, and the dial 19a is turned to cause rotation of said rotary arm 17. In this stage, infrared rays are applied to the 25 pupil of the patient 14 through the infrared lamps 16 to permit the television camera to work, whereby the motion of the pupil or pupillary reflex is transmitted to the television screen 20. If light of the lamps enters to the diseased or damaged part of the optic nerves, the 30 pupil does not contract and shows no response to the light. In such a case, the position of the light is recorded on a recording-paper.

Push buttons are turned on or off in the similar manner to energize or deenergize lamps 17d in sequence, 35 and at the same time the rotary arm 17 is rotated a full turn, thereby permitting examination of the patient response to rays of various angles.

The device for examining pupillary reflex of the present invention as set forth hereinabove is so adapted that 40 diseases or damages in the retina or optic nervous system are detected and a range of visual field is also observed through the reflex motion of the pupil to the lights rays applied from various angle. Such a pupillary 45 reflex is detected by the infrared camera and reproduced into a visible image on the television screen, so that the motion of the pupil is exactly observed in detail, without any communication from the patient. Thus any person including an aphasic, an older person or child, having speech difficulties, and any patient with general paralysis may be readily examined. These devices of the present invention contribute to an objective analysis of the disease.

What is claimed is:

1. An optical device for diagnosis of reflexes of the 55 pupil of an eye of an individual, comprising:

A. A substantially hemispheric shell covering the entire range of the human visual angle; said shell provided at its apex with an opening for 60 a TV camera and an infra-red source of light opening spaced from said apex;

B. A TV infra-red camera mounted with its lens at the apex of said hemispheric shell directed toward the fulcrum of said hemispheric screen;

C. an infra-red source of illumination mounted adjacent said infra-red source opening spaced from said camera to emit rays toward said fulcrum;

D. means for positioning said individual with his eye in the fulcrum of said hemispheric shell;

E. means for directing infra-red light from said infra-red source to the pupil of said eye;

F. means for illuminating said pupil with a spot of visible light, including an arch-shaped rotary arm provided with a plurality of lamps on its internal surface;

G. means for moving said spot of light in said hemispheric shell to vary the direction from which said spot of light appears to originate to said pupil.

2. A device for examining pupillary reflex of a patient in an erect position as claimed in claim 1 further comprising a casing for covering the upper portion of a patient's body and having the said hemispheric shell therein and switch means for controlling the position, size, intensity and period of the said illumination located outside of the said casing.

3. An optical device for diagnosis of reflexes of the pupil of an eye of an individual, comprising:

A. means for illuminating said pupil with a spot of visible light;

B. means for moving said spot of light in a hemispheric concave area to vary the apparent angular direction from which said spot of light appears to originate to said eye of said individual;

C. means for positioning said individual so that said eye is centered on said hemispheric concave area;

D. means for directing infra-red light at said centered eye;

E. television camera means for generating a video signal representative of the pupil reflexes of said eye as viewed under said infra-red light; and

F. television display means for displaying said video signal as a viewable picture;

said hemispheric concave area being defined by a concave arm rotatably mounted along an axis intersecting with the centered position of said eye; and

said illuminating means being mounted on the concave side of said arm, whereby

movements of said spot of visible light cause a pattern of reflex responses by said pupil in dependence upon the varying apparent angle of said spot as viewed from the position of said eye, allowing said pattern of reflex responses to be viewed as televised under said infrared light.

4. An optical device for diagnosis of reflexes of the pupil of an eye of an individual, comprising:

A. a concave hemispheric light reflecting screen,

B. a source of a directional beam of visible light directed to impinge upon said screen,

C. means to vary the direction, intensity and duration

of said beam,

D. at least one source of infrared light,

E. means connected to said screen to direct the emanation of infrared rays from the infrared source,

F. a chin support for the chin of said individual,

G. means to position said chin support,

H. means to align said means to vary the direction of said beam and said means to position said chin support with each other and with said means to direct the emanation of infrared rays and with said hemispheric screen to permit positioning of said pupil at about the center point of said hemispheric screen, thereby permitting travel of said directional beam of visible light over the interior of said hemispheric

screen such that both the visible light and the infrared rays illuminate the center point of said hemispheric screen,

- I. said means to vary the direction of said beam including means to do so at varying angles thereof within the range of a normal visual field of the individual, whereby the pupil is examined at different angles in different areas, and
- J. optical detecting means in optical alignment with said center point of said hemisphere for photographing said eye by infrared light to observe the responses of the eye to visible light.
- 5 5. A diagnostic optical device as claimed in claim 4, said at least one source of infrared light comprising two infrared sources.
- 10 6. An optical device according to claim 4, said at least one source of infrared light being a source of a single infrared beam, said means to align including means to align said infrared beam for continuous intersection with said illuminating light beam.
- 15 7. An optical device according to claim 8, wherein said optical detecting means comprises a television camera.
- 20 8. An optical device for diagnosis of reflexes of the pupil of an eye of an individual comprising:
  - A. a diagnostic table adapted for the head of said individual,
  - B. a light-excluding chamber for the individual's head surrounding said table,
- 25

- C. at least one hemispherical arm with a bearing support rotatably mounted in a ceiling of said chamber,
- D. A central opening within said ceiling and said bearing support,
- E. a television camera, including a lens barrel of said television camera protruding through said opening,
- F. means to rotate said bearing support with said hemispherical arm,
- G. means to position said pupil in alignment with a center line of said lens barrel in said chamber,
- H. means to move the head of said individual vertically in alignment with the geometric center of said hemispherical arm,
- I. a plurality of sources of visible light beams in said arm symmetrically arranged in rows with sequentially decreasing light intensities in each row,
- J. said light beams being in convergence with the geometric center of said hemispherical arm which intersects with the position of the pupil to be examined, and
- K. at least one source of infrared light rays placed to illuminate said geometric center in optical correlation with said visible light beams, and means to control the operation of said visible light beams, said infrared rays and said means to rotate said hemispherical arm.
